UNITED STATES PATENT OFFICE.

THOMAS JAMES, OF BRADDOCK, PENNSYLVANIA.

CRANE.

SPECIFICATION forming part of Letters Patent No. 453,006, dated May 26, 1891.

Application filed September 15, 1890. Serial No. 364 962. (No model.)

To all whom it may concern:

Be it known that I, THOMAS JAMES, of Brad-
dock, in the county of Allegheny and State of
Pennsylvania, have invented a new and use-
5 ful Improvement in Cranes, of which the fol-
lowing is a full, clear, and exact description,
reference being had to the accompanying
drawings, forming part of this specification,
in which—

10 Figure 1 shows in side elevation the jib of
a crane and my improved mechanism for
moving the trolley longitudinally on the jib.
Fig. 2 is a plan view thereof.

In cranes used in mills and steel plants it
15 is necessary to employ some power mech-
anism for moving the trolley back and forth on
the jib. A hydraulic cylinder is the mech-
anism most available for this purpose, but as
heretofore used the cylinder must have a
20 length of stroke equal to the length of travel
of the trolley, and the inconvenient length of
such cylinder and its great weight have so
incumbered the cranes as to impede their
25 operation and materially to increase their
cost. To remedy this serious practical diffi-
culty is the object of my invention, which
makes it possible to use a cylinder of short
stroke and of comparatively small and con-
30 venient size and light weight.

35 In the drawings, 2 represents the mast of a
crane. 3 is the jib, 4 a usual strengthening
strut or brace, and 5 is the trolley, to which
the burden of the crane is connected and
which is adapted to be moved back and forth
35 on the jib.

6 is a double-acting cylinder set on the jib
and having the usual fluid inlet and discharge
ports 7 8 at its ends. This cylinder is of short
stroke, and its plunger 9 is attached to a cross-
40 head 10, which moves in a suitable guide 11.
This guide preferably forms part of a stand-
ard or casting 12, which is bolted to the jib,
as shown in Fig. 1. The cross-head is con-
nected with the trolley by a system of levers
45 a b c d, constituting a parallelogram, the le-
vers a and b being pivotally connected at one
end to the cross-head, the levers c d pivotally
connected with the trolley, and the levers a
and b being pivotally connected with the le-

vers c and d, respectively. These levers are 50
preferably made of flanged beams, such as
I-beams, star-iron, &c., so that they shall
have sufficient rigidity without excessive
weight. In order to maintain proper paral-
lelism of the levers and to cause them to act 55
in the manner hereinafter described, I con-
nect the levers a and b by diagonal lever-
arms or toggles 13 to a fixed point on the jib,
which point may be on the standard 12. The
levers a b c d constitute a lazy-tong system of 60
levers, and their action is to multiply the ex-
tent of motion of the plunger 9. Thus if the
plunger be projected to the end of its stroke
from its most retracted position, (shown in
Fig. 1,) the effect is to straighten the lazy-tong 65
levers into nearly upright positions and to
retract the trolley a distance much greater
than the length of the plunger's stroke, as
indicated by dotted lines. A reverse move-
ment of the plunger will project the trolley 70
on the jib.

The advantages of my improvement will
be appreciated by those skilled in the art.
The trolley-moving mechanism is reduced to
a very small compass, expense is saved, and 75
by affording more space on the jib for the
operation of the trolley the effective capacity
of the crane is correspondingly increased.

Modifications in the form and arrangement
of the parts within the scope of my invention, 80
as hereinafter defined, will suggest themselves
to the skilled mechanic.

I claim—

1. In crane mechanism, the combination,
with the trolley and jib, of a motor adapted 85
to move the trolley on the jib, and lazy-tong
levers connecting the moving part of the mo-
tor with the trolley and adapted to multiply
the motion of the motor, substantially as and
for the purposes described. 90

2. In crane mechanism, the combination,
with the trolley and jib, of a motor adapted
to move the trolley on the jib, and levers a, b,
c, d, and 13, constituting lazy-tongs, connect-
ing the moving part of the motor with the 95
trolley, substantially as and for the purposes
described.

3. In crane mechanism, the combination,

with the trolley and jib, of a motor adapted to move the trolley on the jib, a cross-head guide and a cross-head connected with the moving part of the motor, and lazy-tong levers connecting the cross-head with the trolley, substantially as and for the purposes described.

In testimony whereof I have hereunto set my hand this 9th day of September, A. D. 1890.

THOMAS JAMES.
